UNITED STATES PATENT OFFICE.

WILLIAM H. LAKE, OF BROOKLYN, NEW YORK.

LUMINOUS SIGN.

Application filed April 13, 1928; Serial No. 269,827.

This invention relates to improvements in luminous signs and has particular reference to a portable movable sign for use in dark places.

5 The primary object of the invention is to provide a luminous sign which may be used as a program in moving picture houses which are usually so dark that a patron is prevented from reading an ordinary printed 10 program. With the aid of the device the program may be referred to when desired and the printed matter can be distinctly read to the satisfaction of the user, and without annoyance to surrounding patrons. The device 15 will also be found useful by persons not familiar with the language in which the captions of the moving picture are printed, as the sign strip may contain corresponding captions in their home language which may 20 be followed as the picture is shown, thus aiding a foreigner in intelligently following the theme of the moving picture, which would otherwise be uninteresting.

Another object of the invention is to provide 25 a luminous sign which includes a casing having a window therein, a windable stencil strip movable past the window beneath which a movable luminous strip is arranged, the luminous strip being subjected 30 to the action of artificial light to produce a soft glow of light for reflection through the stencil strip as the stencil strip moves past the window opening where the stencil indicia may be visibly displayed in the 35 dark.

Another object is the provision of a compact luminous sign which may be conveniently carried for reference purposes in the dark, and in which the sign strips may be 40 easily changed when desired.

With these and other objects in view, the invention resides in certain novel construction and combination and arrangement of parts, the essential features of which are 45 hereinafter fully described, are particularly pointed out in the appended claims, and are illustrated in the accompanying drawing, in which:—

Figure 1 is a perspective view of my improved luminous sign.

Figure 2 is a horizontal sectional view therethrough.

Figure 3 is a vertical longitudinal sectional view on the line 3—3 of Figure 2.

Figure 4 is a similar view on the line 4—4 of Figure 2.

Figure 5 is a vertical transverse sectional view on the line 5—5 of Figure 3.

Figure 6 is a similar view on the line 6—6 of Figure 3 with the top cover section 60 removed and the top cover section swung to a partially open position.

Figure 7 is a horizontal sectional view through a modified form of my invention.

Figure 8 is a vertical longitudinal section 65 view on the line 8—8 of Figure 7.

Referring to the drawings by reference characters, the numeral 10 designates the preferred embodiment of my invention illustrated in Figures 1 to 6 inclusive which includes an elongated box-like structure embodying an inner rectangular frame 11, a bottom section 12 hinged to said frame as at 13, and a removable top cover section 14 having a window opening 15 therein closed 70 by a transparent glass panel 16. Journalled in the frame are spaced transverse rollers 17 and 18 about which an endless luminous strip 19 passes. The strip 19 is constructed 75 of a paper body 20 having its outer face coated with a layer of luminous paint 21 which, when subjected to the action of light, will throw off a glow which remains for a reasonable period of time. The top lead of the luminous strip underlies the window, 80 while the lower lead is subjected to the action of artificial light from electric lamps 22 which receive their electric current from a dry cell battery 23 supported in a battery carrier 24 mounted on the frame 11. A 85 switch 25 mounted on the top cover section is arranged in circuit with the lamps and battery to control the lighting of the lamps when required. The lamps being in a light chamber will act upon the luminous side of 90 the lower lead of the luminous strip, and cause the strip to glow, which remains in such state until after the strip has passed the window opening. The strip being movable at a relatively slow speed, is kept in a 100 luminous condition and serves as a backing for a movable stencil sign strip 26 which moves over the luminous strip in its movement from one winding spool 27 to another 105 winding spool 28 journalled transversely in the frame 11 adjacent one end thereof. The sign strip passes over guide rollers 29 in its passage from one winding spool to another. The sign strip 26 has stencil or cut-out opening 30 therein which represents the sign 110 indicia and through which the light glow from the luminous strip passes as the stencil

indicia successively passes the window opening, and which becomes clearly visible when read in the dark.

For the purpose of imparting simultaneous movement of the sign strip and luminous strip, I apply a removable crank handle 31 to one end of the spool 28 which is journaled in the frame 11 and serves to support one end of the spool, whereupon the spool 28 containing a wound sign strip may be removed and another substituted therefor. However, the top cover section is first removed and the bottom section 12 swung downward upon its hinge joint as shown in Figure 6 of the drawings. The spool 28 has a gear 32 fixedly mounted thereon which meshes with an idler gear 33 journaled on one side of the frame, and which idler gear meshes with a gear 34 fixed to the spool 27. By turning the crank handle in one direction it will cause the sign strip to wind about the take-up spool 27 and unwind from the spool 28, whereupon opposite turning of the crank will rewind the strip upon the removable spool 28. Each sign strip must have its free end threaded over the respective guide rollers and connected with the spool 27 which is similar in some respects to the threading of a film strip in a camera. The luminous strip 19 is movable simultaneously with the sign strip by providing a gear 34 on the spool 27 which meshes with an idler gear 35 journaled on one side of the frame and which meshes with a gear 36 fixed to the roller 17. The gear ratio between the driven parts is such that the luminous strip travels at the same rate of speed as the sign strip so that no rubbing will occur between the sign strip and the luminous strip which might tend to scratch or rub off the painted surface.

From the foregoing description, it will be seen that a spool containing a sign strip having suitable stencil indicia thereon may be inserted and threaded into the device, whereupon turning movement imparted to the crank will cause the sign strip to pass the window so that it may be visibly read in the dark, as the glow from the luminous strip passes therethrough. The light glow produced by the luminous strip is soft so that the stencil matter clearly stands out free of glare. Although certain uses to which the device may be put have been set forth, I do not care to restrict myself thereto as the principle may be embodied in display signs for advertising purposes if desired.

In Figures 7 and 8 of the drawings, I have illustrated a modified form of my invention in which similar reference characters refer to like parts hereinbefore described in the preferred form. In this embodiment, I dispense with the continuous movable luminous strip and stencil sign strip, and in lieu there-

of, I employ a sign strip 26' windable and unwindable upon the spools 27 and 28. One of the surfaces of the strip contains the indicia which is printed thereon with luminous paint 19'. As the strip passes from one spool to the other, the luminous lettering is subjected to the light from the lamps 22 which causes them to glow and remain in such condition until they have been moved past the window. The upper lead of the strip 26' is supported upon a plate 35 disposed behind the window to prevent sagging of the same. The principle is the same as in the preferred form, i. e. the subjecting of the luminous indicia to the action of artificial light and the successive movement of the indicia past a window.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:—

1. A device of the class described comprising a casing having a window and a light chamber therein, a luminous strip movable through said light chamber and disposed behind said window, and a stencil sign strip movable between said luminous strip and said window.

2. A device of the class described comprising a casing having a window and a light chamber therein, a luminous strip movable through said light chamber and disposed behind said window, a stencil sign strip movable between said luminous strip and said window, and means for imparting simultaneous movement to said luminous strip and stencil sign strip.

3. A device of the class described comprising a casing having a window and light chamber therein, an endless luminous strip disposed behind said window and movable through said light chamber, a pair of winding spools within said casing, a stencil sign strip having its ends respectively connected to said spools, said strip overlying said luminous strip and movable past said window, and means for imparting simultaneous movement to said luminous strip and said stencil sign strip.

4. A device of the class described comprising a casing having a window therein, an endless luminous strip movably mounted within said casing behind said window, electric lamps within said casing for effecting luminosity of said luminous strip, winding spools journaled within said casing, and a stencil sign strip disposed between said window and said luminous strip and windable on said spools.

5. A device of the class described comprising a casing having a window therein, an endless luminous strip movably mounted within said casing behind said window, electric lamps within said casing for effecting luminosity of said luminous strip, winding spools journaled within said casing, a stencil sign strip disposed between said window and said luminous strip and windable on 10 said spools, a crank handle operatively con-

nected to one of said spools, and gear means for imparting winding movements to said spools and simultaneous movement to said luminous strip.

6. In a sign, a travelling luminous strip 10 movable past a source of light, and a stencil sign strip disposed over said luminous strip.

In testimony whereof I have affixed my signature:

WILLIAM H. LAKE.
